(57) **CLAIM**

The ornamental design for a container with overcap, as shown and described.

DESCRIPTION

FIG. 1 is an isometric top, front and right side view of the container with overcap showing our new design;

FIG. 2 is a front elevational view of the container with overcap of FIG. 1;

FIG. 3 is a rear elevational view of the container with overcap of FIG. 1;

FIG. 4 is a right side elevational view of the container with overcap of FIG. 1;

FIG. 5 is a left side elevational view of the container with overcap of FIG. 1;

FIG. 6 is a top plan view of the container with overcap of FIG. 1;

FIG. 7 is a bottom plan view of the container with overcap of FIG. 1; and,

FIG. 8 is an isometric top, front and right side view of the container with overcap showing a second embodiment of our new design.

The broken lines are included for the purpose of illustrating portions of the container with overcap that form no part of the claim to the embodiment in which they are shown
